H. T. SCOTT ET AL

SAFETY DEVICE FOR TANKS

Filed Oct. 31, 1925

Fig. 1.

Fig. 2.

UNITED STATES PATENT OFFICE.

HENRY T. SCOTT AND LUCIEN EARL RONE, OF WICHITA FALLS, TEXAS.

SAFETY DEVICE FOR TANKS.

Application filed October 31, 1925. Serial No. 66,112.

This invention relates to improvements in safety devices for use within oil tanks and contemplates the provision of shut off means therein which will completely discharge the 5 contents of the tank when the same becomes inflamed.

Another object of my invention is the provision of a check valve arranged within the bottom of a tank and communicating with 10 the operating means which when released by the burning of the supporting means therefore, will automatically open the check valve and allow the contents of the tank thus inflamed to pass outwardly through the pipe 15 from the said tank into a reservoir and thus choking the inflamed contents whereby a material saving of the oil is thus obtained from the use of the above entitled invention.

With the above and other objects in view, 20 the invention further includes the following novel features and details of construction, to be hereinafter more fully described, illustrated in the accompanying drawings and pointed out in the appended claim.

25 In the drawing:—

Figure 1 is a sectional view of a tank showing my present invention applied thereto.

Figure 2 is a fragmentary elevation of 30 the tank showing my invention in operation in allowing the contents of the tank to be discharged therefrom.

Referring to the drawing in detail, where- 35 in like characters of reference denote corre- sponding parts, the reference character 10 indicates a tank and 11 a discharge pipe therefore which tank and discharge pipe are of the usual and well known construction and form no part of the present application for letters patent, but are merely shown for 40 purposes of illustration in bringing forward the novel advantages of the above entitled invention.

The invention resides in the provision of a 45 valve body 12 carried upon the bottom of the tank 10 and communicating therewith and the discharge pipe 11 and having included therein a pivoted flap valve 13, the purpose of which will be presently apparent.

Fulcrumed as 14 upon the upper free end 50 of a supporting bar 15 held in a vertically

disposed position by a brace bar 16 is a swinging boom 17 having a counter-balancing weight 18 included upon one end and a chain or similar connecting device, as indicated at 19, secured to its opposite end and 55 the upper side of the flap valve 13. A frus- tro-conical shaped bell 20 supported by an inflammable supporting cord or rope, as indicated at 21, upon the under side of the tank top, suspends a chain 22 from its under side 60 having connection with one end of the swing- ing boom 17 adjacent the counter-balancing weight 18.

In the mode of operation of the present invention it is clearly apparent and manifest 65 that when the safety device is thus normally arranged in the position, as clearly illus- trated in figure 1 of the drawing, in holding the flap valve 13 in a closed position and that when some act exercised, by an act of 70 God or public enemy, inflames the contents of the tank 10, it will be noted that the flames upon the top of the substance thus contained, such as oil in this instance, will burn the sup- porting cord or rope 21 and the bell 20 will 75 be caused to float upon the surface of the substance in the tank 10 and in so doing re- lease the swinging boom 17 in order that the latter will swing to the position, as clearly illustrated in Figure 2 of the drawing, to 80 open the flap valve 13 whereby the said con- tents will pass outwardly through the dis- charge pipe 11 and thus choke the flames of the burning substance or contents of the tank 10 when being discharged within a reservoir, 85 not shown.

The invention is susceptible of various 90 changes in its form, proportions and minor details of construction, and the right is here- in reserved to make such changes as prop- erly fall within the scope of the appended claim.

Having described our invention what is 95 claimed is:—

A safety device for tanks comprising a 95 valve body and discharge pipe therefor, a supporting arm and brace bar carried within the bottom of the tank, a lever eccentrically fulcrumed upon the supporting bar and having one end disposed directly above the 100

discharge pipe, a weight carried upon the opposed end of the lever, a flap valve carried within the valve body and having connection with the lever, a fusible element carried within the top of the tank, a conical shaped bell suspended from the fusible element, and a chain establishing connection be-

tween the bell and the weighted end of the lever.

In testimony whereof we affix our signatures.

HENRY T. SCOTT.
LUCIEN EARL RONE.
